UNITED STATES PATENT OFFICE.

LEE DE FOREST, OF NEW YORK, N. Y.

OSCILLATION-RESPONSIVE DEVICE.

No. 836,071.

Specification of Letters Patent.

Patented Nov. 13, 1906.

Original application filed January 18, 1906, Serial No. 296,615. Divided and this application filed May 19, 1906. Serial No. 317,722.

To all whom it may concern:

Be it known that I, LEE DE FOREST, a citizen of the United States, and a resident of New York, in the county of New York and 5 State of New York, have invented a new and useful Improvement in Oscillation-Responsive Devices, of which the following is a specification.

My invention relates to devices for detecting feeble electrical currents or oscillations, in general, and especially such currents or oscillations which are developed in wireless-telegraph receiving systems.

The object of my invention is to provide 10 an oscillation detector or responder of great simplicity and sensitiveness and one which, inasmuch as it does not depend for its operation upon any variation of resistance of an imperfect electrical contact or any variation 15 of the apparent resistance or counter electromotive force of a polarization-cell, requires no adjustment when employed for receiving wireless-telegraph signals.

With these objects in view, my invention 20 comprises a receptacle inclosing a sensitive, gaseous conducting medium, the conductivity of which does not depend upon heating the same; a wave-intercepting means associated with said gaseous conducting medium where- 25 30 by the feeble electrical currents or oscillations resulting from the energy absorbed from electromagnetic signal-waves may be impressed upon said gaseous conducting medium to alter its conductivity; and a signal- 35 indicating device operatively connected with said gaseous conducting medium whereby alterations in the conductivity of the latter may be made manifest.

My invention may best be understood by 40 having reference to the drawings which accompany and form a part of this specification and which illustrate diagrammatically two simple embodiments of my invention.

In the drawings, Figures 1 and 2 represent 45 wireless-telegraph receiving systems, provided with the oscillation-responsive device which constitutes the subject-matter of the present invention.

In the figures, A represents a receiving-antenna connected to earth at E and associated with the receptacle B. Two electrodes I are inclosed within said receptacle which may be partially exhausted, and as shown 50 they are sealed in said receptacle. The electrodes I may have any suitable shape, although they are herein shown as disks, and

they may consist of platinum or other suitable material. The gaseous medium intervening between the electrodes I is rendered sensitive to electrical oscillations by connecting said electrodes in circuit with a suitable source of electrical energy which is so adjusted as to render said gaseous medium sensitive to the passage of electrical oscillations across the gap between the electrodes. In 60 Fig. 1 the source of energy is shown at H and may consist of an electric battery. I have found that from twenty-five to one hundred and ten volts is a sufficient potential to employ for the purpose of rendering the gas in 65 said gap sensitive to electrical oscillations, although the potential to be impressed upon the electrodes I by the source H depends upon the nature of the gas intervening between the electrodes and upon the degree of 70 exhaustion maintained within the receptacle B. By employing a higher degree of exhaustion a smaller voltage than that above mentioned may be employed. In both figures the gas may be air or it may be a gas 75 containing compounds of the halogen or halogen salts or it may be mercury-vapor. The passage of electrical oscillations across the gap alters the conductivity of the gas in the gap, probably by changing the speed of the 80 ions in said gas and thereby current variations are produced in the circuit containing the telephone F. In Fig. 1 the telephone F is in series with the electrodes I and the battery H, although it may be electrically connected with said electrodes in any suitable manner.

In Fig. 2, L represents a source of vibratory or alternating electromotive force of a frequency so high that a high-pitch note is constantly heard in the telephone F, or else so high as to exceed the limit of response of the telephone-diaphragm. The advantage in using the source of alternating or vibratory electromotive force is that the voltage may 90 be stepped up by a transformer M to any desired amount, for example from fifty to one thousand volts, and impressed upon the electrodes I. In lieu of an alternating-current generator, such as shown at L in Fig. 2, any suitable source of vibratory electromotive force may be employed. In Fig. 2, the telephone F may be included in series with the circuit containing the secondary of the transformer M and electrodes I, or it may be 100 electrically connected with said electrodes in any suitable manner. The effect of the pas-

sage of high-frequency oscillations across the gap between the electrodes I may be increased in the telephone by including a battery *J* in series with the telephone. In such case the conductivity of the gas in said gap, effected by the high-potential alternating current, will allow the relatively low potential direct current from the battery *J* to flow in the circuit containing the telephone and the electrodes, and the passage of electrical oscillations across said gap between said electrodes will produce sudden changes in the conductivity of said gas and therefore in the amplitude of the current flowing in the telephone-circuit.

As shown in Figs. 1 and 2, the electrodes *I* are connected in series with the antenna *A*, but it will be understood that the particular mode of associating the oscillation-responsive device with the antenna forms no part of the present invention and that any suitable system of circuits may be employed with said oscillation-responsive device.

I do not wish to be limited to the particular embodiments of my invention which I have herein disclosed, inasmuch as many modifications may be made therein by those skilled in the art without departing from the spirit of my invention.

This application is a division of my application Serial No. 296,615, filed January 18, 1906.

I claim—

1. An oscillation-responsive device, comprising a partially-exhausted receptacle, two separated electrodes sealed in said receptacle, and a circuit including a source of electrical energy connected in series with said electrodes and the gaseous medium intervening between the same, the said source of electrical energy being so adjusted as to render the said gaseous medium sensitive to electrical oscillations.

2. An oscillation-responsive device, comprising a partially-exhausted receptacle, two separated electrodes sealed in said receptacle, and a circuit including a source of electrical energy and a signal-indicating device electrically connected with said electrodes, the said source of electrical energy being so adjusted as to render the said gaseous medium sensitive to electrical oscillations.

3. An oscillation-responsive device, comprising a partially-exhausted receptacle, two separated electrodes sealed in said receptacle, and a circuit including a source of electrical energy and a signal-indicating device connected in series with said electrodes, the said source of electrical energy being so adjusted as to render the said gaseous medium sensitive to electrical oscillations.

4. An oscillation-responsive device comprising a partially-exhausted receptacle, two separated electrodes sealed in said receptacle, a circuit connected in series with said

electrodes and the gaseous medium intervening between the same, means for developing in said circuit a vibratory electromotive force of such character as to render the said gaseous medium sensitive to electrical oscillations, and means whereby electrical oscillations may be impressed upon said gaseous medium.

5. An oscillation-responsive device comprising a partially-exhausted receptacle, two separated electrodes sealed in said receptacle, a circuit connected in series with said electrodes and the gaseous medium intervening between the same, means for developing in said circuit a vibratory electromotive force of such character as to render said gaseous medium sensitive to electrical oscillations, a circuit including a signal-indicating device electrically connected with said electrodes and means whereby electrical oscillations may be impressed upon said gaseous medium.

6. An oscillation-responsive device comprising a partially-exhausted receptacle, two separated electrodes sealed in said receptacle, a circuit connected in series with said electrodes and the gaseous medium intervening between the same, means for developing in said circuit a vibratory electromotive force of such character as to render said gaseous medium sensitive to electrical oscillations, a circuit including a signal-indicating device and a source of electric energy electrically connected with said electrodes and means whereby electrical oscillations may be impressed upon said gaseous medium.

7. An oscillation-responsive device comprising a receptacle, two separated electrodes inclosed within said receptacle, and a circuit including a source of electrical energy connected in series with said electrodes and the gaseous medium intervening between the same, the said source of electrical energy being so adjusted as to render the said gaseous medium sensitive to electrical oscillations.

8. An oscillation-responsive device comprising a receptacle, two separated electrodes inclosed within said receptacle, and a circuit including a source of electrical energy and a signal-indicating device electrically connected with said electrodes, the said source of electrical energy being so adjusted as to render the said gaseous medium sensitive to electrical oscillations.

9. An oscillation-responsive device comprising a receptacle, two separated electrodes inclosed within said receptacle, and a circuit including a source of electrical energy and a signal-indicating device connected in series with said electrodes, the said source of electrical energy being so adjusted as to render the said gaseous medium sensitive to electrical oscillations.

10. An oscillation-responsive device comprising a receptacle, two separated electrodes inclosed within said receptacle, a circuit con-

5 nected in series with said electrodes and the gaseous medium intervening between the same, means for developing in said circuit a vibratory electromotive force of such character as to render the said gaseous medium 10 sensitive to electrical oscillations, and means whereby electrical oscillations may be impressed upon said gaseous medium.

11. An oscillation-responsive device comprising a receptacle, two separated electrodes 15 inclosed within said receptacle, a circuit connected in series with said electrodes and the gaseous medium intervening between the same, means for developing in said circuit a vibratory electromotive force of such character 20 as to render said gaseous medium sensitive to electrical oscillations, a circuit including a signal-indicating device electrically connected with said electrodes and means whereby electrical oscillations may be impressed 25 upon said gaseous medium.

12. An oscillation-responsive device comprising a receptacle, two separated electrodes inclosed within said receptacle, a circuit connected in series with said electrodes and the 25 gaseous medium intervening between the same, means for developing in said circuit a vibratory electromotive force of such character as to render said gaseous medium sensitive to electrical oscillations, a circuit including a signal-indicating device and a source of electric energy electrically connected with said electrodes and means whereby electrical oscillations may be impressed 30 upon said gaseous medium.

In testimony whereof I have hereunto subscribed my name this 10th day of May, 1906.

LEE DE FOREST.
